C. E. SMITH

PORTABLE SAW

Original Filed May 17, 1921

Patented Mar. 11, 1924.

1,486,808

UNITED STATES PATENT OFFICE.

CURTIS E. SMITH, OF ST. JOSEPH, MISSOURI.

PORTABLE SAW.

Original application filed May 17, 1921, Serial No. 470,333. Divided and this application filed July 31, 1922. Serial No. 578,719.

To all whom it may concern:

Be it known that I, CURTIS E. SMITH, a citizen of the United States, residing at St. Joseph, in the county of Buchanan and State 5 of Missouri, have invented certain new and useful Improvements in Portable Saws, of which the following is a specification.

This invention relates to devices for sawing materials such as wood, and is more particularly directed to an adjustable bed for supporting the materials in a number of positions.

An object of this invention is to provide an adjustable bed for supporting material 15 to be sawed in a number of different adjustable positions, whereby any cut of the material desired may be had, the adjustment being such that the material may be provided with a longitudinal groove, thus forming a 20 cut without entirely ripping through the thickness of the material.

Another object of the invention is the provision of a mitre gage in connection with the adjustable bed whereby different kinds 25 of mitre joints may be had.

With the foregoing and other objects in view which will appear as the description proceeds, the invention consists of certain novel details of construction and combination of parts which will be hereinafter more 30 fully described and pointed out in the claims, it being understood that various changes may be made in the construction and arrangement of the parts without departing 35 from the spirit or sacrificing any of the advantages of the invention as set forth in the appended claims.

In the drawing:—

Fig. 1 is a view in perspective of the adjustable table or bed showing longitudinal grooves and a mitre gage and a straight gage used in connection therewith.

Fig. 2 is a perspective view of a modified form of bed with one side inclined at an angle of 45 degrees to the other side.

Fig. 3 is a cross section of Fig. 1.

Fig. 4 is a cross section of Fig. 2.

In order to provide a wider range of usefulness, and for the convenience in the operation of my saw described and claimed in my application filed May 17, 1921, Serial No. 470,333, on which Patent No. 1,450,459 was granted April 3, 1923, of which the present application is a division, I have provided the 55 bed of my saw casing 1 with a bed plate 2

pivotedly connected at one end to the casing by means of two studs 14 projecting from the side of the casing and engaging in slots 14^a in side members 15 as shown in Fig. 2. These side members extend from the under- 60 side of the bed plate and in spaced relation to each other, and are adapted to engage the sides of the casing to hold the bed plate in position. Nuts 13 engage the threaded ends of the studs 14 for locking one end of the 65 side members 15 in position. In the end of each of the side members 15 opposite to the slots 14^a are slots 16 adapted to receive bolts 17 fastened in the side of the casing having on their ends nuts 18. By means of these 70 slots, bolts and nuts, the bed plate may be adjusted to different angular positions in relation to the top of the housing 1. The slots 14^a permit a slight sliding movement of the bed plate when it is adjusted by means 75 of the bolts operating in their respective slots.

On the top face of the bed plate, I have provided on each side of a saw slot 3 there-in, longitudinal grooves 19 adapted to receive a tongue 20 of the mitre gage 21 shown in Figs. 1 and 3. The mitre gage is made of any suitable material with its forward end sheared off at an angle of 45 degrees and its upper face 29 inclined at the same angle to 85 its lower face. At the outer edge of the mitre gage there is a downwardly and inwardly extending lip 22 which engages the edge and part of the under face of the bed plate to hold it in place. When it is desirable, this mitre gage can be locked in position by means of a thumb screw 23, but when I am using the mitre gage for the purpose of holding and positioning the material sawed, the screw is not in use. Otherwise, the 95 tongue 20 operating in the groove 19 cooperates with the lip 22 engaging the longitudinal edge of the bed plate for holding the gage on the bed plate when being adjusted longitudinally of the said plate.

When I desire to saw material of a definite width, I place on one side of my bed plate a straight gage 24 which can be adjusted upon the bed plate and so held by means of a thumb screw 24'.

In the operation of the adjustable bed and mitre gage 21 for forming cuts of various widths, lengths and depths, the material is placed in position on the mitre portion 29 of the gage after the mitre 21 has been 110

properly adjusted. The bed 2 is likewise adjusted to determine the depth of the cut made by a saw operating through the slot 3. The timber is then moved forwardly into the saw when the desired cut is made.

In practice, I have found it often convenient to cut what I call a reverse mitre. For this purpose, I have provided a secondary bed plate 26 of the shape shown in Figs. 2 and 4, a portion 27 of which is horizontally disposed with a portion 28 inclined at an angle of 45 degrees to the horizontal part, the line of intersection between the inclined portion 28 and the horizontal portion being in alinement with the saw when said bed is located in operative relation with the top of the casing 1. In this case the table should be so mounted with the horizontal portion spaced above the housing that the under face of the inclined portion will not contact with the upper end of the housing, as shown in Figure 4. The bed plate shown in Figs. 2 and 4 is provided with grooves 19, same as those shown in Fig. 1 and for the same purpose, the mitre gage being adapted for use upon this form as well as that shown in Fig. 1. By use of the mitre gage 21, shown in Fig. 1, on the inclined portion of the bed shown in Fig. 2 I can cut a double mitre joint. The ordinary double mitre joint is formed by properly adjusting the mitre gage 21 in position on the inclined portion 28 of the bed 26. The material is placed on the mitre element 29 of the gage 21 so that the longitudinal edge of the timber will be alined with the saw.

As the material is moved lengthwise of the bed and in face to face engagement with the mitre element 29 of the gage, the material will be cut on the mitre as desired.

It will be seen that by the use of the gage in cooperation with the movable bed plate 2 or 26, any desired mitre cut may be had, the gage determining the kind of cut while the movable bed plate determines the depth of the cut.

What is claimed is:—

1. In a portable saw, a housing, a bed plate mounted on the housing and adjustable vertically and longitudinally of the top of said housing, longitudinal grooves in the bed plate, a mitre gage having a depending tongue slidable in a groove, means on the gage embracing a longitudinal edge of the bed plate and cooperating with said tongue sliding in the groove for maintaining said gage in position on the bed plate, said gage having an inclined face adapted to support a piece of material to be sawed and a saw slot centrally disposed in the bed plate and in line with the inner edge of the gage.

2. In a portable saw, a housing, a bed plate

mounted on the housing and adjustable vertically and longitudinally of the top of said housing, longitudinal grooves in the bed plate, a mitre gage having a depending tongue slidable in a groove, with a portion of the gage extending beyond the longitudinal side edge of the bed plate and around and beneath said bed plate and embracing a longitudinal edge of the bed plate and cooperating with said tongue sliding in the groove for maintaining said gage in position on the bed plate, said gage having an inclined face adapted to support a piece of material to be sawed and a saw slot centrally disposed in the bed plate and in line with the inner edge of the gage, and means for locking the gage in position on the bed plate.

3. In a portable saw, a housing including two side walls spaced to receive the saw between them, a bed plate mounted on the housing and adjustable vertically and longitudinally of the top of said housing, said bed plate having a horizontal portion and a portion inclined downwardly at an angle to the horizontal portion the angle being adjacent the plane of a saw between the housing walls with the horizontal portion spaced from the top of the housing, longitudinal grooves in the bed plate, a mitre gage having a depending tongue slidable in a groove, means on the gage embracing a longitudinal edge of the bed plate and cooperating with said tongue sliding in the groove for maintaining said gage in position on the bed plate, said gage having an inclined face adapted to support a piece of material to be sawed and a saw slot centrally disposed in the bed plate and in line with the inner edge of the gage.

4. In a portable saw, a housing including two side walls spaced to receive the saw between them, a bed plate mounted on the housing having a horizontal portion the angle being adjacent the plane of a saw between the housing walls and a portion inclined downwardly at an angle to the horizontal portion with the horizontal portion spaced from the top of the housing.

5. In a portable saw, a housing including two side walls spaced to receive the saw between them, a bed plate mounted on the housing and adjustable vertically and longitudinally of the top of said housing, said bed plate having a horizontal portion and a portion inclined downwardly at an angle to the horizontal portion the angle being adjacent the plane of a saw between the housing walls with the horizontal portion spaced from the top of the housing, longitudinal grooves in the bed plate and a mitre gage slidable mounted on the bed plate.

In testimony whereof I affix my signature.
CURTIS E. SMITH.
